UNITED STATES PATENT OFFICE.

EDWIN E. SLICK, OF JOHNSTOWN, PENNSYLVANIA.

FURNACE-ROOF.

1,109,553.

Specification of Letters Patent. Patented Sept. 1, 1914.

Application filed November 29, 1913. Serial No. 803,710.

To all whom it may concern:

Be it known that I, EDWIN E. SLICK, a citizen of the United States, residing at Johnstown, in the county of Cambria and State of Pennsylvania, have invented a new and useful Improvement in Furnace-Roofs, of which the following is a full, clear, and exact description, reference being had to the accompanying drawings, forming part of this specification, in which—

Figure 1 is a top plan view partly broken away showing a portion of a furnace roof constructed in accordance with my invention; Fig. 2 is a vertical section on the line II—II of Fig. 1; Fig. 3 is a cross section on the line III—III of Fig. 1; Fig. 4 is a partial end elevation of the hollow girders; Fig. 5 is an enlarged view similar to Fig. 3, showing the keyed-in repair bricks; and Figs. 6, 7, 8, 9, 10 and 11 are partial cross sections showing modified forms of the girder.

My invention relates to furnace roofs, particularly those employed for metallurgical purposes, and is designed to provide a new and improved roof structure, in which the refractory bricks or blocks are carried on hollow water-cooled girders extending up between and separating the upper parts of the rows of bricks. Heretofore, it has been proposed to support these roofs on water-cooled pipes extending between the bricks, but in such case, the pipes have insufficient structural strength as girders, and are not wholly successful.

According to the present invention, I form a series of girders with side shoulders or enlargements entering recesses in the bricks or blocks, these girders extending up between the rows of blocks and having hollow water-cooled portions. These water-cooled girders afford a strong and efficient structure for carrying the loads; and may be cheaply made and installed. Such girders may be made in any desirable manner, as by pressing up the steel plates into girder form having a hollow space for containing water, by welding or otherwise fastening a pipe to a structural girder, etc.

In the form of Figs. 1 to 5, inclusive, 2 represents girders formed of pressed steel shapes, having enlarged lower portions forming side shoulders 3, the upper meeting faces of the sheets being riveted together, as shown at 4. The bricks or blocks have suitable side recesses to receive the

shoulders on the girders, and hung between the girders in rows, as shown. The ends of the girders preferably extend over and rest upon the side walls 6, 6, and I preferably employ shoes 7, having flat lower faces which rest upon the angles or other structure work 8 of the side walls. These shoes or saddles are suitably shaped to receive the lower portions of the hollow girders, and may slide upon the side walls during expansion and contraction of the furnace. The ends of the hollow girders may be closed in any desirable manner, as for example, by fitted end plates 9, which are welded in place. Each of these plates 9 is preferably provided with two screw-threaded holes, one near the top and the other near the bottom, and the inlet pipe 10 is screwed into one of the lower plug holes at one end, and the outlet pipe 11 similarly screwed into the upper hole at the opposite end. The holes not in use may be closed by screw plugs 12, which may be opened for cleaning, changing the inlet water end for end, etc.

To provide for repairing the bricks without dismantling the furnace, I preferably replace an injured or destroyed brick by the three partial bricks *a*, *b*, *c*, shown in Fig. 5. In these blocks, the outer parts are similar to the outer portions of one of the blocks regularly used, while the middle part *b* is a key block which wedges the other blocks sidewise upon the supporting portions of the girders and holds the parts in place.

Instead of pressing the shape shown in Figs. 1 to 5, I may press up other shapes for the girders, such as shown in Figs. 6 to 11, inclusive. In Fig. 6, the girder 2^a is formed by doubling a sheet or plate on itself, leaving the central portions spaced apart to receive water, the plate portions being flattened together through the rest of the height. Fig. 7 shows the same form as Fig. 6, except that a fitting 13 is provided for the supply or outlet pipe. In the form of Fig. 8, the girder 2^b gradually tapers from its lower end down to the upper parallel portions which are riveted together; and Fig. 9 shows a similar form 2^c, except that here the upper portions of the girder are shaped and welded together, instead of being flat and then riveted. In Fig. 10, I show a form of girder comprising a tube 14, welded or otherwise secured to the lower flanges 15 of an I-beam 16. In this case,

the structural beam affords the desired strength as a girder, while the tube secured thereto acts as a conveyer of the cooling fluid. In Fig. 11, I show a form similar to Fig. 10, except that the girder 17 is formed of structural shapes, giving a built-up shape secured to the pipe.

The advantages of my invention will be obvious to those skilled in the art, since the roof is supported on a series of strong girders, while at the same time the girders are protected from overheating by a water-cooled portion formed therein or secured thereto. A flat roof may thus be provided, giving a simple, strong and long-lived structure.

The supporting girders having water-cooled portions are preferably of a depth considerably greater than their width to give the desirable stiffness and strength for supporting the roof sections. At the same time the water-cooled portions of these girders afford an opportunity for a relatively large cooling surface, if desired, and by combining the girders and water-cooling parts I obtain a compact, simple and efficient roof structure which avoids the necessity for separate or additional supports and affords a long life.

By reason of the large amount of cooled surfaces provided by my construction, the region of cooling effect radiates in all directions from said surfaces in such a way that the entire roof is kept cool, and it should also be noted that I arrange the cooling supports comparatively close together so that the range of the cooling effect of one pipe extends into the cooling zone of the adjoining pipes, so that the roof structure will be fully supported, maintained in position and protected.

The bricks or blocks may be changed in shape, the girders having the water-cooled spaces may be varied widely, and other changes may be made without departing from my invention.

I claim:

1. A furnace roof, comprising a series of girders having lower hollow water cooled portions, connections for circulating water therethrough and rows of bricks or blocks hung on the water cooled portions of the

girders, said girders projecting upwardly above the bricks and blocks; substantially as described.

2. A furnace roof, comprising a series of parallel horizontally extending transverse girders of greater depth than width, having lower hollow water cooled portions, connections for circulating water therethrough, and rows of bricks or blocks supported upon the water cooled portions of the girders, which girders project upwardly above the tops of the blocks; substantially as described.

3. A furnace roof, comprising a series of transverse girders resting on the side walls and formed of steel shapes of greater depth than width, said girders having lower hollow water cooled portions, connections for circulating water through said water cooled portions, and rows of bricks or blocks supported on the water cooled portions of the girders, which girders project upwardly above the tops of blocks and separate their upper portions; substantially as described.

4. A furnace roof having a series of girders with solid upper portions and water cooling cavities in their lower portions, and rows of bricks supported on each side of the lower portion, substantially as described.

5. A furnace roof comprising hollow water-cooled girders, each of a depth considerably greater than its width, and provided with projections on the lower portions of the sides thereof with rows of bricks or blocks supported by said projections, substantially as described.

6. A furnace roof comprising hollow water-cooled girders, each of a depth considerably greater than its width and provided with projections on the lower portions of the sides thereof, said girders being spaced closely together so that the cooling zone of each projects into that of the adjacent girders, with rows of bricks or blocks supported thereby, substantially as described.

In testimony whereof, I have hereunto set my hand.

EDWIN E. SLICK.
